ELECTRON DISCHARGE DEVICE

Donald M. Powers, Boston, Mass., assignor to
 Raytheon Manufacturing Company, Newton,
 Mass., a corporation of Delaware

Application April 13, 1944, Serial No. 530,861

15 Claims. (Cl. 250—27.5)

1 This invention relates to a magnetron oscillator of the plural-anode cavity type which is adapted to generate oscillations of hyper-frequencies having wave lengths of the order of a few centimeters or less.

In devices of this kind it is desirable that the oscillations generated be fed into a transmission system, such as a hollow wave guide, in a direct and efficient manner. It is therefore an object of this invention to couple the energy of the oscillating portions of such a magnetron into a hollow wave guide in a direct, simple and efficient manner.

Another object of this invention is to devise the above type of coupling so that the impedances of the various parts of the system are matched with each other by impedance multiplying or transforming means of simple configuration.

The foregoing and other objects of this invention will be best understood from the following description of exemplifications thereof, reference being had to the accompanying drawings, wherein:

Fig. 1 is a vertical cross-section of one embodiment of my invention taken along line 1—1 of Fig. 2;

Fig. 2 is a transverse cross-section taken along line 2—2 of Fig. 1;

Fig. 3 is a view similar to Fig. 2 of another embodiment of my invention;

Fig. 4 is a fragmentary cross-section taken along line 4—4 of Fig. 3;

Fig. 5 is a fragmentary transverse cross-section of another embodiment of my invention; and

Fig. 6 is a fragmentary cross-section taken along line 6—6 of Fig. 5.

The magnetron illustrated in Figs. 1 and 2 comprises a tubular envelope 1 made of a cylinder of conducting material, such as copper. The ends of the envelope are covered by caps 2 and 3 likewise formed of conducting material, such as copper, and hermetically soldered in place on the ends of the envelope 1. The envelope 1 is formed with a central annular projection 4. A plurality of radially-disposed plates 5 are soldered in place along the inner surface of the projection 4. The inner ends of the radial plates 5 are adapted to serve as anodes and receive electrons emitted from a centrally-disposed cathode 6, which is preferably of a thermionic indirectly-heated oxide-coated type. The cathode 6 is provided with an internal heater 7 and an outer conducting sleeve 8, preferably coated with the usual thermionically-emitting oxide coating. The heater 7 is provided with a pair of end conductors 9

2 and 10 which project from the opposite ends of the cathode structure. One of the conductors 9 may be electrically connected to the cathode sleeve 8, while the other conductor 10 is insulated from said sleeve. The cathode 6 is supported by a pair of lead-in conductors 11 welded respectively to the end conductors 9 and 10. The lead-in conductors 11 pass through glass seals 12 mounted at the outer ends of conducting pipes 13 hermetically fastened through the wall of the envelope 1 adjacent the upper and lower ends thereof.

When such a magnetron is placed between suitable magnetic poles 14 to create a longitudinal magnetic field and the device is energized, oscillations are set up with the opening between each pair of plates 5 operating as a tuned oscillating cavity. These oscillations are fed, by means of a construction to be described below, into a hollow wave guide 15, preferably of a rectangular cross-section and formed of a suitable conducting material, such as copper. The wave guide 15 is wrapped around the outside of the envelope 1, preferably with the long dimension of the cross-section of said wave guide 15 in contact with the external wall of the envelope 1. The wave guide 15 is hermetically soldered to the envelope 1 where it comes in contact with said envelope. The wave guide 15 is closed at one end 16, and is connected at the other end through a choke coupler 17 to an additional wave guide 18 through which the oscillations may be led to an external utilization device. In order to complete the hermetic seal, a glass member 19 may be sealed across that portion of the choke coupler 17 which is connected to the wave guide 15.

In order to feed the oscillating energy directly into the wave guide 15, a plurality of coupling loops 20 are located in selected oscillating cavities between adjacent anode plates 5. One end of each of said coupling loops 20 is firmly and electrically connected to the inner wall of the envelope 1. The other end of each of the loops 20 is connected to a conductor 21 which extends through an opening 22 in the side walls of the envelope 1 into the interior of the wave guide 15 where said conductors 21 serve as exciting probes for said wave guide.

For maximum efficiency the probes 21 should feed energy into the wave guide 15 in the proper phase relation to the wave propagated through said wave guide to reinforce the wave by being in phase agreement therewith. If, for example, the loops 20 are located in cavities which oscillate in time phase with each other, then the probes

21 should be spaced apart along the wave guide 15 by a distance

$$\frac{n_1 \lambda g}{2}$$

where n_1 is an even whole number and λg is the wave length of the radiations within the wave guide 15. If, however, the loops 20 are located in cavities which oscillate 180° out of time phase with each other, then the probes 21 should be spaced apart along the wave guide 15 by a distance

$$\frac{n_2 \lambda g}{2}$$

where n_2 is an odd whole number. The closed end 16 is located the proper distance from the adjacent probe 21, so that radiations which are propagated toward said closed end 16 and are reflected therefrom combine with the radiations propagated in the opposite direction in phase agreement therewith so as to produce a resultant propagation of the hyper-frequency energy in a direction through the wave guide 15 toward the choke coupler 17 and the external wave guide 18.

By the foregoing arrangement the oscillatory energy generated by the magnetron is fed directly into the wave guide through which it is to be fed to an external utilization device in a simple and effective manner.

Instead of using loops 20 and probes 21 for coupling purposes, as described above, other coupling arrangements may be utilized. For example, as shown in Figs. 3 and 4, tapered slots 23 extend from predetermined oscillating cavities within the magnetron through the walls of the envelope 1 and into the wave guide 15. The tapered slots 23 serve as impedance matching elements so that the impedance of the oscillating cavities is matched to the impedance of the wave guide. For this purpose the inner end of each slot 23, looking into the oscillating cavity within the magnetron, is sufficiently smaller than the outer end of said cavity 23, looking into the wave guide 15, so as to produce the necessary impedance matching.

Instead of matching the impedances through tapered slots, as described in connection with Figs. 3 and 4, impedance transforming slots 24, as illustrated in Figs. 5 and 6, may be utilized. Each slot 24 is provided with a section 25 of increased length, looking into the oscillating cavity, and connected with a section 26 of decreased length, looking into the wave guide 15. The shoulder 27 between the sections 25 and 26 introduces an impedance transforming discontinuity which together with the sections 25 and 26 results in the desired impedance matching.

It is desirable that the standing wave ratio adjacent the choke coupler be as low as possible in order that a maximum of energy be propagated through the wave guide section 18. This ratio in the embodiment described above may be reduced by causing the amount of power fed into the wave guide section 15 to increase progressively as the choke coupler 17 is approached. This may be done in Figs. 1 and 2 by adjusting the length of the probes 21 to be progressively greater. Likewise in Figs. 3-6, the coupling slots may be adjusted to be progressively larger. Also the standing wave ratio can be reduced by dissipating some of the energy at the closed end 16 of the wave guide section 15, as by coating the inside surface of said end 16 with a resistance material. Also a slight deviation of the probes of Figs. 1-2 and

75 the slots of Figs. 3-6 from that as described above will tend to reduce said standing wave ratio.

Of course it is to be understood that this invention is not limited to the particular details as described above as many equivalents will suggest themselves to those skilled in the art.

What is claimed is:

1. A high frequency oscillator comprising an electron discharge tube having a plurality of electromagnetically coupled cavity resonators therein, and a hollow wave guide adapted to be excited by said cavity resonators, a plurality of said cavity resonators being directly coupled to said wave guide, said wave guide having a closed end and an opposite end section through which end section the oscillatory energy is led out of the oscillator.

2. A high frequency oscillator comprising an electron discharge tube having a plurality of cavity resonators therein, and a hollow wave guide adapted to be excited by said cavity resonators, a plurality of said cavity resonators being directly coupled to said wave guide at a plurality of points spaced along said wave guide, said wave guide having a closed end and an opposite end section through which end section the oscillatory energy is led out of the oscillator.

3. A high frequency oscillator comprising an electron discharge tube having a plurality of cavity resonators therein, and a hollow wave guide adapted to be excited by said cavity resonators, each of said cavity resonators being directly coupled to said wave guide through an impedance matching slot, said slot having predetermined cross-sectional dimensions looking into said cavity resonator and different cross-sectional dimensions looking into said wave guide, whereby the impedance of said cavity resonator is matched to the impedance of said wave guide.

4. A high frequency oscillator comprising an electron discharge tube having a plurality of cavity resonators therein, and a hollow wave guide adapted to be excited by said cavity resonator, each of said cavity resonators being directly coupled to said wave guide through an impedance matching tapered slot, said slot having predetermined cross-sectional dimensions looking into said cavity resonator and different cross-sectional dimensions looking into said wave guide, whereby the impedance of said cavity resonator is matched to the impedance of said wave guide.

5. A high frequency oscillator comprising an electron discharge tube having a plurality of cavity resonators therein, and a hollow wave guide adapted to be excited by said cavity resonators, each of said cavity resonators being directly coupled to said wave guide through an impedance transforming slot, said slot having substantially uniform predetermined cross-sectional dimensions looking into said cavity resonator and extending through said slot for a predetermined distance and different substantially uniform predetermined cross-sectional dimensions looking into said wave guide and extending the running distance through said slot, whereby an impedance transforming discontinuity is produced within said slot.

6. An electron discharge device comprising a cathode, an anode, said anode having a plurality of electron-receiving portions disposed around said cathode, and a plurality of grooved portions spaced from said first portions and likewise disposed around said cathode, said grooved portions constituting cavity resonators, a hollow wave guide wrapped around said anode, a plurality of

said cavity resonators being directly coupled to said wave guide, said wave guide having an end section through which the oscillatory energy is led out of the oscillator.

7. An electron discharge device comprising a cathode, an anode, said anode having a plurality of electron-receiving portions disposed around said cathode, and a plurality of grooved portions spaced from said first portions and likewise disposed around said cathode, said grooved portions constituting cavity resonators, a hollow wave guide wrapped around said anode, a plurality of said cavity resonators being directly coupled to said wave guide, said wave guide having a closed end and an opposite end section through which the oscillatory energy is led out of the oscillator.

8. An electron discharge device comprising a cathode, an anode, said anode having a plurality of electron-receiving portions disposed around said cathode, and a plurality of grooved portions spaced from said first portions and likewise disposed around said cathode, said grooved portions constituting cavity resonators, a hollow wave guide wrapped around said anode, a plurality of said cavity resonators being directly coupled to said wave guide at a plurality of points spaced along said wave guide, said wave guide having an end section through which the oscillatory energy is led out of the oscillator.

9. An electron discharge device comprising a cathode, an anode, said anode having a plurality of electron-receiving portions disposed around said cathode, and a plurality of grooved portions spaced from said first portions and likewise disposed around said cathode, said groove portions constituting cavity resonators, a hollow wave guide wrapped around said anode, a plurality of said cavity resonators being directly coupled to said wave guide at a plurality of points spaced along said wave guide, said wave guide having a closed end and an opposite end section through which end section the oscillatory energy is led out of the oscillator.

10. A magnetron comprising a cathode, an anode, said anode having a plurality of electron-receiving portions disposed around said cathode, and a plurality of grooved portions spaced from said first portions and likewise disposed around said cathode, said grooved portions constituting cavity resonators, means adjacent said cathode for producing a magnetic field transverse to the discharge path between said cathode and said electron-receiving portions, a hollow wave guide wrapped around said anode, a plurality of said cavity resonators being directly coupled to said wave guide, said wave guide having an end section through which the oscillatory energy is led out of the oscillator.

11. A magnetron comprising a cathode, an anode, said anode having a plurality of electron-receiving portions disposed around said cathode, and a plurality of grooved portions spaced from said first portions and likewise disposed around said cathode, said grooved portions constituting cavity resonators, means adjacent said cathode for producing a magnetic field transverse to the discharge path between said cathode and said electron-receiving portions, a hollow wave guide wrapped around said anode, a plurality of said cavity resonators being directly coupled to said wave guide at a plurality of points spaced along said wave guide, said wave guide having a closed end and an opposite end section through which

end section the oscillatory energy is led out of the oscillator.

12. A high frequency oscillator comprising an electron discharge tube having a plurality of cavity resonators therein, a hollow wave guide adapted to be excited by said cavity resonators, a plurality of said cavity resonators being directly coupled to said wave guide at a plurality of points spaced along said wave guide, said wave guide having a closed end and an opposite end section through which end section the oscillatory energy is led out of the oscillator, and energy dissipating means at said closed end.

13. A high frequency oscillator comprising an electron discharge tube having a plurality of cavity resonators therein, a hollow wave guide adapted to be excited by said cavity resonators, a plurality of said cavity resonators being directly coupled to said wave guide at a plurality of points spaced along said wave guide, said wave guide having a closed end and an opposite end section through which end section the oscillatory energy is led out of the oscillator, and means at said coupling points for progressively increasing the energy fed into said wave guide from said cavity resonators as said opposite end section is approached.

14. A high frequency oscillator comprising an electron discharge tube having a plurality of cavity resonators therein, and a hollow wave guide adapted to be excited by said cavity resonators, each of a plurality of said cavity resonators being directly coupled to said wave guide by a probe at a plurality of points spaced along said wave guide, said wave guide having a closed end and an opposite end section through which end section the oscillatory energy is led out of the oscillator, said probes being progressively longer as said opposite end section is approached.

15. A high frequency oscillator comprising an electron discharge tube having a plurality of cavity resonators therein, and a hollow wave guide adapted to be excited by said cavity resonators, each of a plurality of said cavity resonators being directly coupled to said wave guide by a coupling slot at a plurality of points spaced along said wave guide, said wave guide having a closed end and an opposite end section through which end section the oscillatory energy is led out of the oscillator, said coupling slots being progressively larger as said opposite end section is approached.
